ATTORNEY

UNITED STATES PATENT OFFICE.

JOHN LUNDEEN, OF PORTLAND, OREGON.

BEDCLOTHES CLAMP.

1,416,655.

Specification of Letters Patent. Patented May 16, 1922.

Application filed May 17, 1921. Serial No. 470,294.

To all whom it may concern:

Be it known that I, JOHN LUNDEEN, a citizen of the United States, residing at Portland, in the county of Multnomah and 5 State of Oregon, have invented new and useful Improvements in Bedclothes Clamps, of which the following is a specification.

This invention relates to a device for holding bed clothes in position upon the bed, 10 the principal object of the invention being to provide clamping means for engaging the bed clothes and so arranged that they can be easily and quickly moved from operative to inoperative position or vice versa.

15 Another object of the invention is to provide means whereby the device can be easily and quickly attached to a bedstead.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a diagrammatic view showing the invention in use upon a bedstead.

Figure 2 is an enlarged front view of the device itself.

35 Figure 3 is a similar view of the rear of the device.

Figure 4 is a section on line 4—4 of Figure 1.

Figures 5 and 6 are detail views.

In these views 1 indicates the frame of 40 the device which consists of the bottom bar, the top bar 3 and the end connecting bars 4. This frame is detachably connected with the bed posts at the foot of the bed by means of the clamps 5 connected with the side bars of 45 the frame and engaging the posts 6 of the bed. An angle bar 7 is connected with the top bar 3 by the toggle links 8 and a flat bar 9 is movably connected with the bar 7 by the bolts 10 which are slidably arranged in 50 the holes in the bar 7. Coil springs 11 are placed on said bolts and tend to hold the bars 7 and 9 in spaced relation. The ends of the bar 7 are bent over to form sideways 12 which engage the end bars 4. The toggle 55 links are provided with stops 13 which permit the links to be forced inwardly to an

extent sufficient to hold them in position with the bars 7 and 9 in lowered position with the bar 9 clamping the bed clothes between itself and the bottom bar of the frame. 60 A spring latch member 14 is provided for holding the parts in raised position when not in use or when placed in the closing position.

It will thus be seen that the device can be 65 easily and quickly attached to a bedstead and when the toggle levers are pushed downwardly the device will clamp the clothes and thus prevent them from falling off the bed. When the device is not being used it is simply 70 moved upwardly until the spring latch engages the bar 7 which will hold the parts in raised position.

It is thought from the foregoing description that the advantages and novel features 75 of my invention will be readily apparent.

I desire it to be understood that I may make changes in the construction and in the combination and arrangement of the several parts, provided that such changes fall with- 80 in the scope of the appended claims.

What I claim is:—

1. A device of the class described comprising a frame having a bottom bar, a clamping bar for cooperating with the bottom bar of the frame, a slidable bar, means for yieldingly connecting the same with the clamping bar and toggle levers connecting the sliding bar with the top of the frame. 85

2. A device of the class described comprising a frame having a bottom bar, means for detachably connecting the same with the bedstead, a clamping bar for cooperating with the bottom bar of the frame, a slidable member connected with the clamping bar 95 and toggle levers connecting the slidable member with a part of the frame.

3. A device of the class described comprising a frame having a bottom bar, means for detachably connecting the same with a 100 bedstead, a clamping bar for cooperating with the bottom bar of the frame, a bar slidably mounted in the frame, bolts slidably connecting the clamping bar with the sliding bar, spring means for holding the said 105 bars in spaced relation, toggle links connecting the sliding bar with a part of the frame and a latch member for holding the parts in raised position.

In testimony whereof I affix my signature. 110

JOHN LUNDEEN.
